HERBERT MOLE

RHYS TREVOR JENKINS,

By their Attorneys,

Baldwin Wright

UNITED STATES PATENT OFFICE.

HUGH WARREN LEE, HERBERT MOLE, AND RHYS TREVOR JENKINS, OF NEWCASTLE-UPON-TYNE, ENGLAND, ASSIGNEES TO SIR W. G. ARMSTRONG, WHITWORTH AND COMPANY, LIMITED, OF NEWCASTLE-UPON-TYNE, ENGLAND.

AMMUNITION HOIST.

Application filed February 16, 1925. Serial No. 9,550.

To all whom it may concern:

Be it known that we, HUGH WARREN LEE, HERBERT MOLE, and RHYS TREVOR JENKINS, subjects of the King of Great Britain, residing at Elswick Works, Newcastle-upon-Tyne, England, have invented new and useful Improvements in Ammunition Hoists, of which the following is a specification.

This invention relates to ammunition hoists in which the projectile is caused to ascend or descend a trunk by means of lifting arms pivoted to sliders reciprocating in the trunk, such as are described in specifications Nos. 1,366,394 and 1,392,583, and the object of the present invention is to provide means for delivering the projectile or other body from the lifting arms to the delivery tray and also improved means for operating the tray.

According to this invention a slider, when in the position with the lifting arm raised so that the projectile rests upon a delivery tray, engages with a roller on the end of an arm fixed to a shaft to which is fixed another arm connected by a link to a projection upon a stop or hook which is pivoted to the underside of the delivery tray. To the second of the arms on the shaft is attached a spring. As the slider passes the roller the shaft carrying the arms is caused to turn and the link connecting the second arm to the projection on the hook is moved, causing its pivot on the projection to coincide with the axis upon which the delivery tray turns and causes the hook to engage with the underside of the projectile. On the slider is a cam groove in which runs a roller at one end of a lever whose other end is connected by means of a link to the underside of the delivery tray, the cam groove being such that as the slider moves upwards the delivery tray is turned upon its axis into a horizontal position, and as the hook is also pivoted to the underside of the tray it turns with it and remains in position engaging the projectile.

When lowering ammunition the reverse action takes place, the projectile being placed on the tray when in a horizontal position, and as the slider moves downwards the tray is tilted upwards into the trunk and the end of the slider ceasing to engage the roller on the first mentioned arm, the second arm is

caused to resume its original position owing to the action of its spring, and the hook is withdrawn from engagement with the projectile, which is then retained by the lifting arm on the slider and is ready to be lowered.

The accompanying drawings illustrate mechanism made in accordance with this invention. Figures 1 and 2 are elevations partly in section of a delivery tray at the top of a hoist; Figure 1 shows a projectile delivered to the tray by one of the lifting arms and Figure 2 shows the tray after it has been tilted.

a is a slider having a lifting arm *b*, and *c* is a tray pivoted at *d* and in the position shown in Figure 1 a body *e* has just been delivered by the arm *b* to the tray. At the same time the upper end of the slider *a* engages with a roller *f* on an arm *g* fixed to a shaft *h* to which is fixed another arm *j* connected by a link *k* to a projection *l* on a hook *m* pivoted at *n* to the underside of the tray *c*. The arm *j* is attached to a spring *o* which tends to keep the roller *f* in contact with the slider *a*.

As the slider *a* passes the roller *f* the shaft *h* is caused to turn and the link *k* is moved causing its pivot on the projection *l* to coincide with the pivot *d* of the tray *c*, and the hook *m* is caused to turn and engage with the body *e* as shown in Figure 2. The tray *c* is then turned upon its pivot *d* by means of a cam groove *p* in which runs a roller on one end of a lever *q* whose other end is connected by a link *r* to the underside of the tray *c*. As the hook *m* is pivoted to the underside of the tray *c* it turns with it and remains in position engaging the body *e*.

When lowering ammunition the reverse takes place, the body *e* being placed on the tray *c* when in a horizontal position and as the slider *a* moves downwards the tray *c* is tilted upwards and the end of the slider *a* ceasing to engage the roller *f* on the arm *g*, the arm *j* is caused to resume its original position by the action of the spring *o*, and the hook *m* is withdrawn from engagement with the projectile which is then retained by the lifting arm *b* and is ready to be lowered.

What we claim is:—

1. In an ammunition hoist, a slider, an arm on the slider, a pivoted tray, a stop on

the tray, means for turning the tray and means for moving the stop into engagement with a body on the tray both actuated by the slider.

5. 2. In an ammunition hoist, a slider, an arm on the slider, a pivoted tray, a stop pivoted to the tray, a projection on the stop, a link pivoted to the projection, means for causing the pivot of the link to coincide with the axis of the tray, means for turning the tray and means for moving the stop into engagement with a body on the tray.
3. In an ammunition hoist, a slider, an arm on the slider, a pivoted tray, a stop pivoted to the tray, a projection on the stop, a link pivoted to the projection, means actuated by the slider causing the pivot of the link to coincide with the axis of the tray, means for turning the tray and means actuated by the slider for moving the stop into engagement with a body on the tray.

4. In an ammunition hoist, a slider, an arm on the slider, a pivoted tray, a stop pivoted to the tray, a projection on the stop, a shaft, two arms fixed to the shaft, one actuated by the slider, a link connecting the

other to the projection and means for turning the tray.

5. In an ammunition hoist, a slider, an arm on the slider, a pivoted tray, a stop pivoted to the tray, means for moving the stop into engagement with a body on the tray, a cam groove in the slider, a pivoted lever, one end actuated by the cam groove, and a link connecting the other end to the tray.

6. In an ammunition hoist, a slider, an arm on the slider, a pivoted tray, a stop pivoted to the tray, a projection on the stop, a shaft, two arms fixed to the shaft, one actuated by the slider, a link connecting the other to the projection, a cam groove in the slider, a pivoted lever, one end actuated by the cam groove, and a link connecting the other end to the tray.

In testimony that we claim the foregoing as our invention we have signed our names this 27th day of January 1925.

HUGH WARREN LEE.

HERBERT MOLE.
